UNITED STATES PATENT OFFICE.

JAMES FRANK PLACE, OF MONTCLAIR, NEW JERSEY.

LAMP.

SPECIFICATION forming part of Letters Patent No. 392,823, dated November 13, 1889.

Application filed November 18, 1887. Serial No. 255,467. (No model.)

To all whom it may concern:

Be it known that I, JAMES FRANK PLACE, a citizen of the United States, and a resident of Montclair, Essex county, New Jersey, have 5 invented certain Improvements in Air-Distributing Caps for Lamps, of which the following is a specification.

My invention relates to that class of lamps which have cylindrical wicks and a central 10 shaft, and particularly to the air-distributing cap which surmounts the air-tube of such a lamp; and the object of my invention is to improve the construction of such air-distributing cap, and also the manner of mounting it on the 15 wick-tube. In this class of lamps, where all the air passing up through the annular wick-tube is entrapped in the perforated distributing-cap and then supplied to the flame, the cap has been made to slip over the upper end of 20 the inner wall of the wick-tube and extend down into the space occupied by the wick. The objection I find to this construction is that the wick when raised is liable to displace the cap. In constructions where the cap ex- 25 tends down into the air-passage through the wick-tube and rests on a ledge therein the tube is more or less obstructed and its construction is necessarily special—that is to say, the wick-tube of the lamp must be specially 30 constructed to receive the cap. My construction avoids these objections, and also when the lamp is not burning and the wick projects above the tube the wick is apt to rest against some part of the cap, and thus cause the oil to 35 be drawn up by capillary force and led into the air-tube. In lamps provided with my cap this does not take place.

I will now describe my invention with reference to the accompanying drawings, where- 40 in—

Figure 1 is a perspective view of an ordinary lamp provided with my improvements. Fig. 2 is a sectional diagrammatic view of the air-distributing cap and a part of the annular 45 wick-tube of the lamp on which said cap is mounted, and Fig. 3 is a diagrammatic view which represents the two parts or elements of the cap separated.

A represents an ordinary annular wick- 50 tube; x, the wick therein, and B the cap mounted on the upper end of said tube and

closing the air-passage through the same—that is to say, all the air that passes up through the air-passage y in said tube must first pass into said cap B, from whence it is supplied to 55 the flame through the numerous perforations in the sides or walls of said cap.

I make the cap B in two parts, as seen best in Fig. 3, the base portion in that figure being designated by b and the crown by b^x. The base 60 comprises the following features: A cylindrical socket-piece, 1, which extends down into the inner tube, a, of the wick-tube, and which should fit the latter snugly; an exteriorly-formed flange or shoulder, 2, which rests on 65 the top of tube a, and which should not project outwardly beyond the outer face of said tube; a contracted perforated wall, 3, which is drawn in with a view to keep it clear of the wick x of the lamp; a shoulder, 4, on which the 70 crown b^x rests, and a tubular extension, 5, which extends up into the crown. The crown comprises a deflecting top plate, 6, preferably provided with a conical depression, as shown, and a perforated side wall, 7.

The object in making the cap in two parts 75 detachable from each other, as shown, is partly to facilitate the construction and render it more economical, and partly to facilitate the cleaning of the cap.

The object in constructing the base of the cap to slip down into the wick-tube is to prevent it from interfering with the wick, and the object in forming the flange or shoulder 2 exteriorly so as to rest on the top of the wick-tube 85 is to enable the cap to be used on any ordinary wick-tube, and thus avoid the special construction of the latter to adapt it to the cap. This mode of mounting the cap also effects a material economy in the construction of the burner. 90 The object in drawing it or contracting the diameter of the wall 3 just above the flange 2 is to keep it out of contact with the tip of the wick, and thus prevent the oil raised by the wick from flowing over into the air-passage. 95

The object in providing a tubular extension 5 of less diameter than the crown of the cap is to compel a portion of the air supplied to the flame to rise to the upper part of the cap before it passes to the flame. It will be understood that the air supplied to the inside of the flame in a lamp of this kind is drawn in by the 100

draft, and the purpose of all these devices is, primarily, to supply this air in evenly-distributed jets to the "flame-wall." Where a simple gage or perforated cylinder is used, the air 5 will take the shortest and easiest course to the flame, and thus the air-supply will not be sufficiently dispersed to produce the best results. My construction is designed especially with a view to furnishing to the flame substantially 10 the proper proportion of air from every part of the perforated wall-surface of the cap.

When the lamp is burning, the air drawn up through the wick-tube is all fed to the flame 15 through the perforations in the cap. A portion passes out through the perforations in the contracted concave portion 3. The remainder passes up to the upper part of the cap, and is deflected outward and downward along its perforated wall, the tubular extension 5 compelling a portion of the air to rise to and pass out 20 at the upper zone of perforations in the wall, while the remainder flows down into the annular space 8 between the extension 5 and outer wall, 7, and finally out at the lower zone of 25 perforations in said wall. The aggregate areas of the perforations of the cap will be proportioned properly to the area of the air-passage through the wick-tube, and these areas will also be proportioned in such a manner as to 30 properly distribute the air-supply to the flame. The arrows in Fig. 2 indicate the course of said air-currents through the cap.

It will be observed that the tubular extension 5, which admits air to the upper part of 35 the cap, has a much more limited area than the socket-piece 1, through which air enters from tube *a*. Therefore, to allow for the free passage of all the air to the flame, the perforations in the portion 3 of the base member are given 40 sufficient area in the aggregate to allow the ex-

cess of air to pass, the remainder passing up through extensions 5.

I usually construct the deflecting-plate 6 separately from the perforated wall 7 and secure them permanently together by seaming 45 in a well-known way.

In Fig. 1 I have not attempted to show as many perforations as the cap B will usually have. In fact, I do not limit myself in this respect, it being only requisite that the air shall 50 be evenly distributed.

Having thus described my invention, I claim—

1. The combination, with the annular wick-tube, of an air-distributing cap adapted to be 55 mounted removably on the top of said wick-tube, said cap having a socket-piece which extends down into the said wick-tube, an exteriorly-arranged flange or shoulder which rests on the top of said wick-tube, and a contracted 60 perforated portion, 3, just above said flange, whereby the wick of the lamp is prevented from coming in contact with the cap, as set forth.

2. An air distributing cap for a central- 65 draft lamp, composed of two detachable parts or members, *b* and *b'*, the former having a socket-piece, 1, an exterior flange, 2, a perforated contracted portion, 3, a shoulder, 4, and a tubular extension, 5, and the latter having a 70 deflecting top plate, 6, and a perforated side wall, 7, substantially as set forth.

In witness whereof I have hereunto signed my name in the presence of two subscribing witnesses.

JAMES FRANK PLACE.
